UNITED STATES PATENT OFFICE.

MORRIS L. UTTER, OF ROCKFORD, ILLINOIS.

CULTIVATOR.

SPECIFICATION forming part of Letters Patent No. 276,984, dated May 1, 1883.

Application filed July 27, 1882. (No model.)

To all whom it may concern:

Be it known that I, MORRIS L. UTTER, a citizen of the United States, residing in the city of Rockford, in the county of Winnebago and State of Illinois, have invented a new and useful Improvement in Cultivators, of which the following is a specification.

This invention relates to that class of cultivators known as "riding straddle-row cultivators."

The object of this invention is to provide means by which the free or shovel-supporting end of the shovel-beams may be supported in a proper relative position substantially parallel with the line of movement of the machine, when in use, in cultivating hilled or rowed crops on a hill-side without extra exertion on the part of the operator. To this end I have designed, constructed, and applied the device represented in the accompanying drawings, in which--

Figure 1 is a plan view of portions of a cultivator with my improvements represented in place thereon, of which Fig. 2 is a front elevation, partly in section, on dotted line x.

In the figures, A represents the carrying-wheels, mounted to revolve on the axle-arms of the axle-tree B.

At C are represented converging beams fixed to axle-tree B, and forward thereof connect with the tongue D.

At E is represented a transverse beam fixed to the under side of the converging beams and tongue in advance of the axle-tree.

F are drag-bars or shovel-beams having a hinged connection, with pendants fixed to the end portions of the transverse bar.

H represents a two-part sway-bar, suitably connected and suspended on links I, having a pivotal connection on suitable supports rising from the main frame. The depending end portions of the sway-bar have a free connection with the drag-bars.

All the above parts in every particular are substantially the same, joined in the same manner, and for the same purpose as like parts of the cultivator patented to me November 27, 1877, and numbered 197,503.

At a are represented brackets, in this instance of bar material round in section, fitted to engage the axle-tree and the converging beams, to which they are securely fixed.

At b is represented a spiral spring having a free ring or thimble connection with the horizontal portion of the bracket fixed to the main frame in such a manner that the spring will be free to slide lengthwise on the bracket.

At c is represented an angle-formed bracket-plate fitted to engage the central or crown portion of the sway-bars, to which it is removably fixed in an adjustable manner by means of a set or clamping screw-bolt. The horizontal portion of this bracket is provided with a series of holes, d, provided on one side with a radial slot. The free end of the spiral spring is provided with a hook-formed stud provided with a lip or blade projecting from the side of its end portion in key-like form. This hook-formed stud with its key-like blade is adapted to enter the radially-slotted holes d in the bracket-plate. The relative position of the radial slot in the holes in the bracket-plate and the key-like blade of the hook-stud are such that when the stud is inserted in the plate the key-like blade will turn away from the radial slot, and will prevent the accidental disengagement of the stud from the plate, but in such a manner as to be readily disengaged or re-engaged.

In a cultivator having my improvement attached, when in use on a hill-side, the spring on the side of the cultivator on the upper side of the hill is connected with the bracket-plate and adjusted in its connection therewith as near as may be within the provisions of the device to exert a sufficient force to hold the shovel-beams in a position substantially parallel with the direction of its forward movements, and in such a manner as to enable the operator without extra exertion to carry the shovel-beams to either side for the purpose of properly cultivating the plants, substantially in the same manner as in the use of the cultivator on level land without the employment of my improvement. These springs are arranged on both sides of the machine in such a manner that either can be used to adapt the machine for use in a back-and-forth movement on the same hill-side or in the same direction on opposite hill-sides. In this instance I have employed a spiral spring in one piece, having a slipping or sliding connection on their bracket-supports on the main frame to permit of a lateral movement of the shovel-beams be-

yond the capacity of the springs; but this same result can be obtained without the slipping action of the spring by the employment of a centrally-link-jointed two-part spring, in which instance its outer end may have a suitably fixed link or hinge connection with the main frame.

From the foregoing it will be seen that I produce a spring-connection between the main frame and the shovel-beams of the cultivator, by which I render it an efficient machine for the cultivation of crops on the hill-side.

I claim as my invention—

1. The combination, with the supporting-frame of a cultivator, and with the sway-bar having a suitable connection with the shovel-beams, of a spring connected to the main frame and adapted to be connected with the sway-bar, for the purpose and substantially as described.

2. The combination, with the supporting-frame of a cultivator, and with the sway-bar having a suitable connection with the shovel-beams, of springs connected to the main frame upon opposite sides thereof, either of which is adapted to be connected with the sway-bar, for the purpose and substantially as described.

3. The combination, with the supporting-frame of a cultivator, and with the sway-bar having a suitable connection with the shovel-beams, of a spring connected to the sway-bar and to the supporting-frame, and capable of a sliding movement on its bracket-connection with said supporting-frame, substantially as and for the purpose set forth.

4. The combination, with the supporting-frame of a cultivator, and with the sway-bar having a connection with the shovel-beams, of a spring having a bracket-connection with the main frame and an adjustable detachable connection with the sway-bar, substantially as and for the purpose set forth.

5. The combination, with the sway-bar connected with the shovel-beams, of an angle bracket-plate detachably connected with the sway-bar, and a spring connected with the supporting-frame, and having an adjustable detachable locking-connection with the angle bracket-plate, substantially as and for the purpose set forth.

MORRIS L. UTTER.
